[57] CLAIM

The ornamental design for a tape transport, substantially as shown and described.

DESCRIPTION

FIG. 1 is a front and left side perspective view of a tape transport showing my new design;

FIG. 2 is a front elevational view thereof;

FIG. 3 is a left side elevational view, the right side being a mirror image.

The top and rear are conventionally plain.

FIG. 1

FIG_2

FIG. 3
